UNITED STATES PATENT OFFICE.

GEORGE J. COMNINOS, OF PITTSBURGH, PENNSYLVANIA.

HEATER.

1,128,588.

Specification of Letters Patent. Patented Feb. 16, 1915.

Application filed June 29, 1914. Serial No. 847,812.

To all whom it may concern:

Be it known that I, GEORGE J. COMNINOS, a subject of the King of Greece, and residing in the city of Pittsburgh, in the 5 county of Allegheny and State of Pennsylvania, have invented or discovered new and useful Improvements in Heaters, of which the following is a specification.

My invention consists in new and useful 10 improvements in gas furnaces.

The objects in view are the provision of a heating device which may be safely used in a room, such as a garage, or building where- 15 in explosive gases or substances are present, and which while of inexpensive construction, is also substantial and durable and utilizes the greatest possible percentage of heat value for heating the air.

The objects are accomplished by construct- 20 ing my heater so that, whether the same be used alone as where the room containing the same is to be heated, or is incased in an outer casing as where other rooms are to be heated, no air or fumes from the room in which the 25 heater is located can either enter the combustion chamber or gain access to the ignited fuel or the products of combustion. Air from without said room is supplied by in- 30 closed ducts to the combustion chamber while the air supplied to the air compartments of the heater is conducted thereto by inclosed ducts which pass through the compartments through which the products of 35 combustion travel.

The construction and arrangement of the 40 heater are novel as is also the method of supplying air thereto.

Other novel features of structure and ar- 45 arrangement of parts will appear from the following description.

In the accompanying drawings, which are merely intended to be illustrative of the principles of my invention and not to limit the scope of the same to the construction 50 shown, Figure 1 is a vertical central section through the heater; Fig. 2 is an elevation of the fumes drum taken at right angles to Fig. 1 and the outer wall being partially broken away to show the baffles; Fig. 3 is a cross section taken along the line III—III 55 in Fig. 1 looking upwardly, the door being broken away in section for the sake of clear- ness; Fig. 4 is a front elevation of the heater broken away at the top and the door being shown open to expose the gas valves; Fig. 5

is a side elevation showing the heater within a furnace casing, said casing being partially broken away to show the heater, and Fig. 6 is a detail section along the line VI—VI in Fig. 5 showing the method of supplying air 60 to both the interior of the casing and to the combustion chamber.

The following is a detailed description of the drawings, reference being first had to Figs. 1, 2, 3 and 4.

A is an annular combustion chamber formed by the outer wall 1 and the wall 2 which forms the circumferential wall of a central air chamber B. Both of said walls rest upon a base ring C which closes the 70 bottom of the chamber A.

3 represents a plurality of inclosed air ducts leading from without the wall 1 through the chamber A into the chamber B. The upper portion of the wall 1 is prefer- 75 ably provided with a plurality of glass or mica closed peep holes 4.

Upon the top of wall 2 is mounted the annular burner member D which I prefer to divide horizontally into two parts so that 80 either one or both burners may be used as requirements may dictate. Said burners are of substantially L shape cross-section, thus forming an annular horizontal chamber a and an annular vertical chamber b commu- 85 nicipating with chamber a. The outer wall of chamber b is provided with a plurality of perforations 5 through which the gas escapes in jets to burn in the combustion chamber A. Gas is supplied to the burners by means of 90 pipes 6 which enter the bottom of the chambers a leading through the chambers B and A and provided with valves 7 and mixers 8 in the chamber A. The heads of valves 7 extend through snugly fitting holes in the 95 door E in the wall 1 and a key 9 may be inserted in said valves to regulate the same without opening the door E. The pipes 6 are connected with the service pipe 10 prefer- 100 ably provided with a valve 11.

12 is a pilot light pipe extending from the pipe 10 through the wall 1 and provided adjacent to the perforations 5 of the burner D with a perforated pilot burner 13 by means of which said burner D may be 105 lighted. Said pipe 12 is preferably pro- vided with a valve 14 without the wall 1.

Air is supplied to the combustion cham- 110 ber A at either side by means of a pair of inclosed ducts or pipes 15, preferably pro-

vided with regulating dampers 16. The pipes 15 are connected to an air supply pipe 17 leading from without the room.

F is a flaring ring provided with a depending neck 18 which fits down within the burner D to hold the ring in place. Said ring extends outwardly toward the wall 1 forming therewith a throat 19.

G is a vertical annular fumes drum resting upon the top of wall 1 and ring F and held in place by means of the strap ring 20. The bottom of said drum G is provided with a series of perforations 21 to admit the products of combustion from the chamber A. The top of said drum is closed. From the top of said drum a fumes pipe 22 leads to the vertical pipe 23, the lower end of said pipe 23 being extended to be connected to the fresh air pipe 17 to provide a check draft for the fumes pipe 22. A damper 24 is provided to regulate the check draft and a damper 25 is provided to regulate the capacity of the fumes escape. The interior of the drum G is provided with inclined staggered baffles 26 to baffle and retard the passage of the fumes to the pipe 22. The center of drum G forms the air mixing chamber H whose open bottom registers with the interior of the ring F and whose top is open to atmosphere. 27 are a pair of horizontal ports extending through the drum G and connecting the chamber H with atmosphere.

A fresh air supply duct 28 leads from one of the ducts 15 through the door box 29 of the door E at a point adjacent to the mixers 8 to insure a sufficient supply of air to the latter.

The operation of the heater is as follows: 40 The valves 7 are opened as well as the valve 14 of the pilot light. The door E is opened and the pilot light ignited. The door E is then closed tightly. The pilot light ignites the burner D, the products of combustion rising in chamber A and ascending through the perforations 21 into the baffled interior of the annular drum G where the fumes are baffled and led back and forward before escaping through the pipe 22, so that the 45 walls of the drum receive the full heating effect of said fumes. The flaring ring F also becomes highly heated from the products of combustion. The combustion of fuel in chamber A is sustained and facilitated 50 by the air admitted through the ducts 15 while the duct 28 supplies the necessary air to the mixers 8. The passage of the fumes through the drum may be regulated by the dampers 24 and 25. Air enters the chamber 55 B through the ducts 3 and becoming heated rises up through the center of the burner D and the ring F into the mixing chamber H where it mixes with and heats the air entering through the lateral ports 27, the heated 60 air then escaping out of the open top of

the chamber H. After the pilot light is once lighted it is not necessary to again open the door E, as the valves 7 may be used to light the burner D or shut the same off, the pilot light being permitted to burn continuously. It is evident that when the door E is closed no possible means of access exists for gases in the room to enter the combustion chamber, fumes drum or fumes pipe of the heater, so that the latter may be used 70 in a garage or similar compartment without danger or fear of explosion. 75

In Fig. 5 I show the heater inclosed in an outer casing from whose crown lead the usual hot air flue pipes 30 for heating other rooms from that in which the heater is installed. In this case the outer casing J is provided with cold air ducts 31 which lead from cold air box 32 connected by large supply pipe 33 to outdoors. In such case, for convenience the pipe 23 may be connected with said pipe 33 to supply the check draft. Where the outer casing J is provided, the ducts 15 which supply the combustion chamber A with fresh air may be extended 80 through the air ports in said casing into the air ducts 31 as shown in Fig. 6. The air entering the air ducts 31 feeds the air ducts 15, 28 and 3 of the heater so that it operates as above described while additional air rises 85 about the heater within the casing, part of which enters the chamber H through the ports 27 and all meeting and intermingling in the crown of the furnace.

As is the case in the use of my heater 90 alone, when the same is used as a furnace with an outer casing, no gases or air from the room in which the furnace is installed can enter the compartments of the heater in which the products of combustion are generated or through which they pass. Thus 95 explosions are positively prevented.

The form of burner shown is important 100 as the gas entering the chamber a from the pipe 6 swirls around in said chamber before entering the chamber b, thus feeding said chamber b and its perforation 105 equally and uniformly for its entire circumference. The entering gas is also heated in chamber a, the walls of which chamber become heated 110 by the air rising from chamber B, thus increasing the pressure of the gas in the burner. 115

It will be seen that the flaring ring F and chamber H, of greater diameter than the throat formed in the axis of burner D permits the heated air to expand and this facilitates the rise of air from the chamber B.

The construction of my heater is economical 125 and the full heating effect upon the fresh air passing therethrough is realized without appreciable loss.

What I desire to claim is:—

1. A gas heater comprising an annular 130
